BOW GUN

Carl E. Watson, R.R. 2, Box 259,
Henderson County, Ky. 42420

Filed Sept. 15, 1967, Ser. No. 8,609

Term of patent 14 years

Int. Cl. D22—02

U.S. Cl. D22—5

FIG. 1 is a perspective view of a bow gun, showing my new design.

FIG. 2 is a view in side elevation of the claimed design, where the opposite side is a mirror image;

FIG. 3 is a view in front elevation of the claimed design; and

FIG. 4 is a view in rear elevation of the claimed design.

I claim:

The ornamental design for a bow gun, as shown and described.
